UNITED STATES PATENT OFFICE.

BENJAMIN LIPPER AND CHARLES KELSH, OF PHILADELPHIA, PENNSYLVANIA, ASSIGNORS TO AUGUSTUS A. LAZARUS, ISAAC A. SCHWARZ, AND BENJAMIN LIPPER, OF SAME PLACE.

DESIGN FOR TRIMMING.

SPECIFICATION forming part of Design No. 23,432, dated July 10, 1894.

Application filed June 11, 1894. Serial No. 514,255. Term of patent 3½ years.

To all whom it may concern:

Be it known that we, BENJAMIN LIPPER and CHARLES KELSH, both citizens of the United States, and residents of Philadelphia, Pennsylvania, have invented a new and original Design for Trimming, of which the following is a specification.

Our design is fully shown in the accompanying drawing which represents a face view of a piece of the trimming.

The background of the trimming consists of cross cords forming at opposite edges of the trimming groups of loops *a*. On this background is face ornamentation consisting of a series of flat bands *b* each carried back

and forth in a zig-zag course across the trimming, the points of the zig-zags meeting in the center of the strip so as to inclose diamond-shaped spaces *d*.

We claim--

The design for trimming, substantially as described and shown.

In testimony whereof we have signed our names to this specification in the presence of two subscribing witnesses.

BENJAMIN LIPPER.
CHARLES KELSH.
